UNITED STATES PATENT OFFICE.

HENRY G. O'BRIEN, OF PITTSBURGH, PENNSYLVANIA.

ROLLING-MILL.

1,236,598.

Specification of Letters Patent. Patented Aug. 14, 1917.

Application filed February 1, 1917. Serial No. 145,895.

To all whom it may concern:

Be it known that I, HENRY G. O'BRIEN, residing at Pittsburgh, in the county of Allegheny and State of Pennsylvania, a citizen of the United States, have invented or discovered certain new and useful Improvements in Rolling-Mills, of which improvements the following is a specification.

My invention relates to improvements in rolling mills, and particularly to continuous mills: that is to say, mills in which the article under treatment, after having been brought to rolling condition,—which, ordinarily, means high temperature—is passed in immediate sequence through a succession of mills. The invention resides in the arrangement of mills; and, while it may be practised in continuous mills of various kinds, I have applied it and shall here show and describe it in application to mills for rolling hot strips of steel or other metal. It will be understood that I mean to include within the scope of my patent, the invention as applied to continuous mills of all sorts.

The objects of my improvements are economy and facility in operation.

The accompanying drawings illustrate a hot strip mill in which the improvements constituting my invention are incorporated. Figure 1 (continued on three sheets as Figs. 1^a, 1^b, 1^c) shows the mill in plan. Figs. 2, 3, and 4 are fragmentary views to much larger scale and show in vertical section the adjacent portions of the pairs of rolls in proper relative positions which form the individual mills 1, 2 and 4 presently to be described. Each of these three Figs. 2, 3, and 4, is set opposite the individual mill which illustrates it; that is to say, Fig. 2 shows in profile the roll pass of mill 1, Fig. 3 the roll pass of mill 2, and Fig. 4 the roll pass of mill 4. Fig. 5 is a view in side elevation of the rolls of the edging machine 6 to be described presently. These rolls are shown detached from the rest of the machinery but in proper relative position for co-operation, and the figure is set opposite the edging machine 6 as it appears in the general view, Fig. 1^b. Fig. 6 is a view in side elevation and in some respects a diagrammatic showing of mills 7, 10, and 11, together with their driving apparatus; this view would be got by taking a section on a plane indicated by the line VI—VI, Fig. 1^b. Fig. 7 is a view in longi-

tudinal vertical section through the edging machine 6 (Fig. 1^b) and it illustrates particularly the guides employed.

I pause to explain—what, perhaps, is obvious—that, in these matters, the term “mill” is used in two senses: Primarily, the word means a pair of rolls (with supporting and driving parts), between which an article under treatment is entrained; by extension, the word is applied to groups of such pairs of rolls; and, then, with still another shade of meaning, to the entire building or plant in which the rolling operations are performed. I have already used the term in its broader and more general sense, in saying that the drawing shows a hot strip mill. More precisely speaking, it shows the entire assembly of instrumentalities which, acting in correlation, receive slabs or billets and shape them to strips. This assembly includes a number of mills (using the term in its particular and more accurate sense); in this instance there are eleven such mills, indicated in order from the receiving to the delivery end of the whole by the numerals 1 to 11. The particular number is not significant, nor important. The drawing, however, shows an actual installation.

Each of these eleven mills consists essentially of a pair of rolls mounted in suitable housings and with suitable accessory appliances and fittings. The rolls of each mill are driven by suitable machinery. In this particular case mills 1 to 5 inclusive are formed of twenty-inch rolls, mills 7 to 11 of sixteen-inch rolls; and, using the word mill again in looser sense, the assembly of roll-stands 1 to 5 is commonly spoken of as the “twenty-inch mill,” and the assembly of roll-stands 7 to 11 as the “sixteen-inch mill.” The roll-stand 6 is unique in certain respects, as will presently appear, and is commonly spoken of as the “edging machine.” It is of course to be understood that the dimensions of the rolls—both absolute and relative dimensions—are unimportant to the invention. I am describing an actual installation.

12 is a heating furnace; it may be of any preferred form. From it slabs and billets are delivered to a conveyer table 13. The construction and mode of operation of this table (though these matters are indicated in the drawings) form no part of my invention.

It will be observed that the mills are arranged in a plurality of rows, so that throughout each row the material advances through one mill after another in a direct line of advance, in a single line of entraining; and, then, after passing through the mills of one row, the material is transferred, to pass through the mills of the succeeding row. In the first row are arranged the mills 5 to 8 inclusive; in the second, mills 9 and 10; and, in the third, mill 11 stands alone. The particular grouping, and the particular number of mills in each row, are not important. Preferably, and for the convenient accomplishment of my invention, 15 these rows of mills are arranged side by side in parallel arrangement: that is to say, the successive lines of entraining, A—B, C—D, and E—F are parallel. The mills 7, 10, and 20 11 are arranged opposite one another, in a line G—H transverse to the lines of entraining previously alluded to; and mills 8 and 9 are situated on one side of this transverse line, while all the other mills 25 (1—6, inclusive) are arranged on the other side of this line.

The successive instrumentalities which operate upon the advancing material may be briefly noted and characterized. The slab 30 or billet as it advances upon table 13, and before entering the roll-pass of mill 1, passes a horizontal shear 14. The provision of a shear at this point is advantageous, in that the slab or billet as it passes to the mill can be cut to the length required. This makes 35 for economy, reducing the amount of scrap trimmed from the fabricated or partly fabricated material.

The first mill, 1, is an "edger"; that is to 40 say, a mill which engages the opposite edges of the slab or billet, and reduces it in the matter of width. The rolls of this mill are grooved rolls, and they receive the slab or billet when turned so as to stand on edge, in 45 vertical position. The profile of the roll-pass of this mill 1 is shown to larger scale in the fragmentary sectional view, Fig. 2. Thus, in this first edging pass, the scale is 50 loosened and is freely separated from both faces of the article.

The second mill, 2, is a "flat," a mill of smooth-surfaced rolls, between which the material turned to horizontal position is engaged over its opposite extended surfaces, 55 and reduced in the matter of thickness. This is indicated in Fig. 3, a fragmentary section to larger scale through the roll-pass of mill 2. Inasmuch as the material passing from mill 1 and entering mill 2 requires 60 to be turned from vertical to horizontal position, it is desirable to space mills 1 and 2 a sufficient distance apart that the material shall pass entirely from mill 1 before it enters mill 2. In the actual installation which 65 I have made this distance is 15 feet.

The third mill, 3, is again a "flat"; and, since there is no turning, there is no such necessity for space between mills 2 and 3 as between mills 1 and 2. In the installation I have referred to the placement of the machinery makes this distance 18 feet. 70

Mill 4 is a second "edger," the rolls are grooved. The profile of the roll-pass of this mill 4 is shown to larger scale in the sectional view, Fig. 4. The material after 75 passing from mill 3 and before entering mill 4 must be turned from horizontal to vertical position.

Mill 5 is again a "flat"; and, accordingly, the material passing from mill 4 in vertical 80 position, is turned to horizontal to enter mill 5.

In rolling relatively wide strips (which ordinarily are relatively short) it is, generally speaking, necessary that the material be entirely freed from one mill before it is turned (from horizontal to vertical position, or from vertical to horizontal) to enter the next succeeding mill; but, in rolling relatively narrow strips, a point is reached when the 90 article has been so far reduced in thickness that its forward end advancing to a mill-pass may be turned through an angular rotation of 90° while its rear end remains still engaged in the pass of the next adjacent 95 mill. In the actual installation which I am describing the interval between mills 3 and 4 is 32 feet, and the interval between mills 4 and 5 is the same, 32 feet. And it will be understood that this interval is sufficient to 100 accommodate wide (and short) pieces, and permit them in the course of rolling to extend between the mills, free from end to end, and to allow them to be moved from one of the positions named to the other without twisting, at the same time, narrow strips (which ordinarily will be longer), if they are of greater length than the space interval, 32 feet, may be twisted to properly enter the successive roll passes. 110

Mill 5 is the last of the mills with twenty-inch rolls; mills 7—11 are equipped with sixteen-inch rolls; and, excepting only the "edging machine" 6, all the remaining mills (6—11) are "flats." The edging machine 6 is 115 the last instrumentality directly determining the width of the strip. The rolls of the edging machine are vertically arranged, so there is no turning of the strip as it passes from the "flat" mill 5, nor is there any turning of the 120 strip as it advances from the edging machine 6 to the next succeeding mill 7, which also is a "flat." The vertically arranged rolls of the edging machine (it will be understood that in all these matters I am describing an 125 actual installation, in which the invention is exemplified) are adjustable in their spacing; they are grooved to receive the advancing material; and they are provided with a plurality of pairs of opposite grooves, ordi- 130

narily of different depth. All this is sufficiently illustrated in Fig. 5, which is a view in elevation and to larger scale of the rolls of the edging machine, detached, but in 5 relative positions for operation. The delivery end of the feed table over which the material approaches the edging machine is vertically adjustable, to the end that the material may be caused to enter one pair 10 of grooves or another, as may be desired. This matter of guiding the strip to and through the edging machine is accomplished by the instrumentalities shown in Fig. 7. Upper and lower plates 29 and 30 15 form a passageway for the advance of the strip. This passageway will ordinarily flare both rearwardly and forwardly, as shown in the drawings. A conveyer plate 31 carries the material advancing from mill 5 to the 20 passageway formed by and between plates 29 and 30 above and below and the rolls constituting the edging machine 6 on either side. Plates 29 and 30 are, as has been said, 25 vertically adjustable, to guide the advancing material through one or another of the plurality of passes through the edging machine.

Mills 7-11 inclusive are all alike, in that they all are formed of sixteen-inch rolls, and in that they all are "flats." The spacing 30 between successive mills in the same line is no longer of necessity sufficient to allow the article under treatment to pass in its entirety from one mill before entering another. Suitable tables are provided, extending 35 to the first mill and from the last mill, and in the intermediate spaces between mills; these tables are of suitable construction, but with them my invention is not primarily concerned, and it is sufficient to mention them. At the delivery end of each row 40 of mills A-B and C-D is a transfer device, for carrying the material to the receiving end of the next row; thus, the transfer devices 15 transfer material under treatment 45 from the end B of the first row of mills to the adjacent end C of the second row. (The direction of advance in adjacent rows is reversed.) And, in like manner, the transfer devices 16 carry the material from the delivery end D of the second row to the receiving end E of the third. These transfer 50 devices will of course be multiplied as the number of rows of mills is multiplied. Such devices are well known, and particular description of them is here unnecessary.

In addition, there is a transfer device 17 for engaging material, while still in row A-B and before it reaches the last mill 8 in that row, and for carrying it to row 60 C-D, at a point between mills 9 and 10. Thus mills 8 and 9 may be cut out and the rolling operation shortened accordingly. The significance and value of this will presently be dwelt on. It will be understood, 65 and should be noted here in passing, that

(but for the provision presently to be described), in order to allow the material to be so transferred from line A-B to line C-D before mill 8 is reached, mill 8 should be remote from mill 7 at a sufficient interval 70 to allow the entire article to come through mill 7 from end to end without reaching to mill 8, that it may be transferred by apparatus 17. The actual distance between mills 7 and 8 in the installation to which 75 I have made repeated reference is 55 feet.

I have just alluded to a provision which, in so far as it may be resorted to, requires a modification of the last statements. Mills 8 and 9 may be removable, so that they may 80 when desired be picked up by cranes and set aside; the spaces between the conveyer tables left by their removal may be bridged by suitable plates, and then it will be understood the material advancing from mill 7 85 may be of such length as to extend beyond the point where mill 8 normally stands, and transfer devices 15 and 17 may coöperate to carry the material from the line of entraining A-B to the line C-D. 90

I have said that the particular construction of the transfer tables forms no part of my present invention. It will, nevertheless, be apparent to any mill man reading my drawings that the tables are in the main 95 tables whose surfaces are equipped with and indeed consist of "live" rolls—that is to say, power driven rolls. I note here a circumstance and feature of construction which, though aside from my invention, may 100 well be mentioned in a description of this particular installation: The tables on the delivery side of mill 8 and on the feed side of mill 9 are not roll-equipped. This is a mere matter of preference. The table on 105 the feed side of mill 9 is, however, provided with pairs of feed rolls 27 which may open to receive and close to engage the strip carried to them and may then impel the strip to the pass in mill 9. 110

From the final roll pass, in mill 11, the finished strip advances over a table 18 to a suitable receiver. This receiver may be a reel 28, or it may be a storage table 19 arranged adjacent table 18 to which the finished material may be borne by suitable transfer mechanism. On this table 19 an accumulation of successively rolled strips may collect, cooling; and from this table 19 the cooled strips may one by one be transferred again to the table 20 on which they are carried to shears 21. I have said that a reel for the finished strip may be placed at the remote end of table 18; it may be placed elsewhere, if desired; for instance, it may 115 be placed adjacent mill 11, on its delivery side, and beside the proximate end of table 18, where I have set the reference letter X.

It remains to speak of the driving mechanism, and of the speed of the rolls. Mills 130

1-5 inclusive are, it will be observed, driven from a single source of power, in this case the electric motor 22; the edging machine 6 is driven by its own motor 23; mill 7 is driven by motor 24; mills 8 and 9, by motor 25; mill 11, by motor 26; while mill 10, arranged as has been said in intermediate position between mills 7 and 11, is so connected that it may, at pleasure, be driven, together with mill 7, by motor 24, or, together with mill 11, by motor 26.

It will be observed of mills 7-11, inclusive, that 8 and 9 are arranged to be driven by a single motor and are required to roll the material, one in one direction, the other in the other; and that mills 7, 10, and 11 are arranged to operate in pairs in like manner, 7 and 10 at one time forming such a pair, and 10 and 11 at another time. And it will be understood that, to effect these ends, mills 7, 8, and 11 (the mills which when paired with others stand nearer the motors) are three-high mills; and that, in each pair of mills, the middle roll of the three coöperates in one of the two mills with the roll arranged above it, and, in the other mill, with the roll beneath; thus rolling in opposite directions is effected. This is illustrated in Fig. 6—in some respects a diagrammatic showing of what appears in actual proportions in Fig. 1^b. Coupling members 32 may be employed, to connect mill 10 either with motor 26 (of relatively high speed), as shown, or, transferred to point *m*, with motor 24 (of relatively low speed).

Variable speed motors are used throughout to drive the mills; and, following well established practice, the speed of the successive mills (and this means, of course, the surface speed of the work-engaging parts) increases, in accordance with the elongation of the material under treatment.

The speed of the rolls of the edging machine 6 is preferably separately adjustable, and is under immediate control of the operator, that, as operation proceeds, disturbances otherwise due to variations in speed of material advancing from mill 5 may be avoided.

Having now pointed out the essential characteristics of this mill, my invention may readily be particularized: It consists in doubling the line of entraining upon itself, as in the lines of mills A—B and C—D; in arranging the three mills 7, 10, and 11 in alinement, and in driving them by two motors, the middle mill, 10, being capable of being driven from either; in arranging part of the mills (in this case 8 and 9) on one side of this alinement of the mills 7, 10, and 11, while the other mills (in this case 1-6) are arranged on the opposite side; and in providing the additional transfer mechanism 17, immediately beyond mill 7 and be-

tween it and mill 8. In other words, the instrumentalities co-act to effect a switching of the material in the course of its advance through the series of rolls. This switching effect, when resorted to, cuts out mills 8 and 9; and, accordingly, as mills 8 and 9 are used or are switched out, the mill 10 is connected either to be driven by the motor which drives mill 11, or by the motor which drives mill 7. If the strips are to be rolled to relatively fine gage, say to a thickness of .125 inch or less, the entire series of mills will be employed. In that case mill 10 will preferably be connected to be driven by motor 26. But, if strips of relatively great thickness are to be rolled—say coarser than .125 inch,—mills 8 and 9 are not employed; mill 10 is preferably connected to be driven by motor 24, and the material as it passes from mill 7 is transferred from line A—B to line C—D and enters next mill 10, skipping mills 8 and 9. In this latter case, as has been said, mills 8 and 9 may, if desired, be set aside, and transfer mechanisms 15 and 17 may act as a single transfer mechanism to convey longer strips from line A—B to line C—D.

It will be understood (and I have intimated as much in what has been said) that the mill I have now described (and again I use the word "mill" in its general sense) is an actual embodiment of my invention in a hot strip mill, and is described as an exemplary embodiment of it. My invention is not limited to details nor to what is circumstantial in the foregoing description. The ensuing claims define the essential features of the invention; and they, it will be understood, may be introduced in the construction of continuous mills generally, regardless of whether the material to be rolled is of metal or something else, regardless of whether it is heated or not, and regardless of whether it is the rolling of a strip which is to be accomplished or of some other shape.

I claim as my invention:

1. In a rolling-mill installation, a succession of mills, means for moving material in transit through the succession from a point in the line of feed to rearward of one of the intermediate mills to another point in advance of such intermediate mill without passing through such mill, two mill-driving motors, and means for connecting a mill situated in advance of the intermediate mill mentioned either with one or with the other of the said motors.

2. In a rolling-mill installation including a succession of mills arranged in a plurality of lines of entraining, means arranged in one line of entraining at a point intermediate the length thereof and intermediate two of the mills forming that line of entraining for transferring material while in course of being rolled from such line of entraining

to another line, together with means for driving one of the mills in that other line of entraining now at one speed and now at another.

5. 3. In a rolling-mill installation including a succession of mills arranged in a plurality of lines of entraining, means for transferring material in course of rolling from one line of entraining to another, one of said 10 mills being removable from its position in such succession.

4. In a rolling-mill installation including a succession of mills arranged in three parallel lines of entraining, three mills, one in each 15 line, arranged in transverse alinement one with another, two motors, one at either end of such transverse alinement of mills, operative connection from each motor to the mill at the adjacent end of the said trans- 20 verse line, and means for operatively connecting the intermediate mill of said transverse line alternately either with the one or with the other of said motors.

5. In a rolling-mill installation the combination of a succession of three mills arranged in two lines of entraining, two of 25 said mills, the first and the third in the order of operation, arranged one in each of such lines of entraining, and the third mill, 30 the second in the order of operation, being removable from its position in such succession.

6. In a rolling-mill installation the combination of three mills arranged in two lines 35 of entraining, and a transfer mechanism; two of said mills, the first and the third in order of operation, arranged one in each of such lines of entraining, and the said trans- 40 fer mechanism arranged on the delivery side of the first of said mills and in its operation conveying material under treatment from the first line of entraining to the second and from the delivery side of the first of said mills to the feed side of the second.

45. 7. In a rolling-mill installation the combination of three mills and two transfer mechanisms; the three said mills being arranged for successive operation in two lines of entraining, and the first and the third of 50 said mills (in their order of operation) being arranged one in each of said lines of entraining, the second mill (in order of operation) being removable, and the said transfer mechanisms being arranged one on 55 either side of said second and removable mill and in operation conveying the material from one of said lines of entraining to the other, and adapted, when said second mill is removed, for coöperative operation upon a 60 single piece of material.

8. In a rolling-mill installation the combination of three mills arranged in two lines of entraining, and two transfer mechanisms, 65 two of said mills, the first and the third in order of operation, arranged one in each of

such lines of entraining, the said transfer mechanisms arranged between the two lines of entraining and in operation conveying material under treatment from the first line to the second, one of said mechanisms being 70 arranged on the delivery side of the mill which stands first in order of operation and in operation carrying material under treatment directly from the delivery side of the first mill to the third, and the other of said 75 transfer mechanisms coöperating to carry the material through all three mills in succession.

9. In a rolling-mill installation the combination of three mills and two transfer 80 mechanisms, the three mills being arranged in two parallel and adjacent lines of entraining, the first and the third of said mills, in order of operation, being arranged in transverse alinement, and the second at one 85 side of such alinement, and the two transfer mechanisms arranged, one of them intermediate the alinement of mills one and three and mill two, and the other beyond mill two, on the side remote from the alinement of mills one and three.

10. In a rolling-mill installation a plurality of mills arranged in three lines of entraining and in two transverse rows, the mills of one row being intermediate, in their 90 order of operating upon material, between two of the mills of the other row, and four transfer mechanisms, two of said transfer mechanisms arranged one either side of the row of intermediate mills (as above characterized) and in operation carrying material under treatment from the first line of entraining to the second, a third transfer mechanism carrying material under treatment from the second line of entraining to 105 the third, and the fourth transfer mechanism carrying the finished article from the third line of entraining.

11. In a rolling-mill installation a plurality of mills arranged in three lines of entraining and in two transverse rows, the mills of one of the rows being intermediate, in their order of operating upon material, between two of the mills of the other row, a reel adjacent the third line of 110 entraining, and a table arranged adjacent the third line of entraining, and four transfer devices, two operating to transfer material under treatment from the first line of entraining to the second, these being arranged one on either side of the row of mills characterized above as intermediate, the third transfer mechanism operating to transfer material from the second line of entraining to the third, and the fourth transfer mechanism operating to transfer material from the third line of entraining to said table.

12. In a rolling mill installation the combination of four mills arranged in three

lines of entraining, the first, the third, and the fourth being arranged one in each of such lines, separate motors for driving the first and the fourth of said mills and driving 5 connections alternately established between one or the other of said motors, and the third of said mills.

In testimony whereof I have hereunto set my hand.
